UNITED STATES PATENT OFFICE.

JOHN W. OFFUTT, OF ELLWOOD CITY, PENNSYLVANIA.

GOLF-CLUB.

1,167,922.

Specification of Letters Patent. Patented Jan. 11, 1916.

Application filed September 23, 1914. Serial No. 863,055.

To all whom it may concern:

Be it known that I, JOHN W. OFFUTT, a citizen of the United States, and resident of Ellwood City, in the county of Lawrence 5 and State of Pennsylvania, have invented certain new and useful Improvements in Golf-Clubs, of which the following is a specification.

My invention relates to the construction 10 of golf clubs and more particularly to the means employed in securing the head to the shaft of the golf club.

Golf clubs have been made heretofore, having a hollow metal shaft with a wooden 15 or composition head attached thereto. The tubular metal shaft is necessarily of small diameter and wall thickness. In such golf clubs the end of the tubular shaft extends into a recess or hole in the neck on the head 20 of the golf club, and a pin extending transversely through registering holes in the neck and shaft of the golf club is used to fasten the head to the shaft. The pin is necessarily made of such size that the shaft and neck 25 on the wooden or composition head of the golf club are weakened so as to cause great liability of the shaft being broken or the neck on the head split or broken by the torsional strains set up in striking a golf ball 30 with the club.

An essential or desirable characteristic of a golf club is a sufficient flexibility in the shaft to give to the club what is sometimes called "whip," meaning thereby, as generally understood, that upon contact of the head with the ball as in drive or brassy shots the shaft will bend slightly under the impact of the blow and then tend to straighten during the latter part of the stroke and before the ball moves away from the face of the head of the club, this straightening of the shaft imparting an additional force or momentum to the ball. This desirable quality is secured in wooden clubs, by making 40 the shaft of small section near the neck of the head and of a very tough but flexible material, such as straight grained hickory, but owing to the scarcity of suitable material it is difficult to secure the desired elasticity 45 without unduly decreasing the strength. The desired degree of flexibility can be secured by using a metal tube which also has much greater strength than the toughest wood. This had led to an attempt to substitute metal tubing for wood. But the attempt to use metal tubing has introduced 50

another objection, namely, the difficulty of adequately securing the end of the tube in the neck of the club head owing to the fact that the tube is of small diameter and also 55 to the fact that it is more difficult to unite wood and metal by cement. The metal tube resists torsion or twisting to a much greater extent than wood, but at the same time this force being exerted eccentric to the axis of 60 the shaft tends to turn the head on the shaft and therefore it becomes necessary to secure even a stronger joint or better adhesion between the neck of the head and the metal shaft than between the same parts when all 65 composed of wood.

My invention secures the advantages inherent in the use of metal shafts and overcomes the disadvantages above pointed out with the result that my improved club has 70 greater flexibility and whip than the wooden shaft and secures an adequate connection between the shaft and the head of the club.

The primary object of my invention is to provide a golf club comprising a tubular 75 metal shaft with a composition or wooden head having improved means whereby the tubular shaft is fastened to the head of the club and still further objects of the invention consist in the novel construction and 80 arrangement of parts more fully described hereinafter and specifically pointed out in the appended claims.

Referring to the drawings forming part of this specification, Figure 1 is a plan of 85 a golf club having a tubular metal shaft and having a head secured to the shaft in accordance with my invention. Fig. 2 is a detail sectional plan, on a larger scale, showing the construction of the fastening by 90 which the head is secured to the shaft of the golf club in accordance with this invention. Fig. 3 is a transverse section on the line III—III of Fig. 2. Fig. 4 is a detail plan partly in section, showing a modification in the construction of the end of the tubular shaft to which the head of the golf club is attached, also made in accordance 95 with my invention. Fig. 5 is a transverse section, on an exaggerated scale, taken on 100 the line V—V of Fig. 4.

In the accompanying drawings the numeral 2 designates the head of a golf club having a neck 3 with an opening or hole therein, into which the enlarged end of the 105 tubular shaft 4 of the club extends. The shaft is provided at its upper end with a

handle 5 wrapped with leather, tape or other suitable material in the usual known manner, which enlarges the diameter of the handle and provides a handle of a size which 5 is readily and comfortably gripped.

By reference to Fig. 3, it will be seen that the outer surface of the enlarged lower end of the shaft is provided with a series of alternate ridges and grooves forming a fluted 10 surface. In the construction of Fig. 2 a tubular thimble 6, after being bored and fluted, is heated and placed on the end of the shaft so that upon cooling it shrinks upon the shaft and thereby is rigidly fastened to the shaft 4. The fluted end of the 15 shaft is then cemented or otherwise secured in the opening or hole in the neck 3 of the head 2. The head and adjacent end of the shaft 4 preferably is then wrapped with 20 twine or other binding material 7 in the usual known manner. The flutes on the surface of the enlarged end of the golf club form corresponding or registering flutes in the opening in the neck 3 into which the 25 end of the shaft extends so that the irregular meeting surfaces effectually prevent twisting or turning of the head 2 on the shaft 4 when the golf club is being used.

In the modified construction shown in 30 Fig. 4 the enlargement 8 on the end of the tubular metal shaft is formed integrally, the tube first being expanded to the desired diameter and then being provided with the series of parallel grooves and ridges to form 35 the fluted surface on the enlarged end of such tubular metal shaft. In this construction the head 2 is attached to the enlarged end of the shaft 4 in the same manner as has been described for the construction of 40 Fig. 2.

The advantages of my invention will be apparent to those skilled in the art. By enlarging the end of the tubular end of the shaft, the surface of the shaft engaging 45 with the head is materially increased and by reason of the increased diameter of the end of the tubular shaft the provision of a fluted surface is made possible of a size enabling the head to be securely fastened to 50 the tubular metal shaft without weakening the joint, as is done when pins extending through registering transverse openings in the neck of the golf club head and shaft are

used. The avoidance of using transverse holes in the shaft and head of the golf club 55 materially increases the strength of the club with little or no increase in weight. The engaging fluted surfaces of the shaft and head effectively prevent twisting of the head on the shaft and resist the torsional strains set 60 up in the golf club when being used.

Modifications in the construction and arrangement of the golf club may be made without departing from my invention. 65 Serrated or fluted surfaces may be provided on the end of a tubular metal shaft which is not expanded. Tubular shafts may be enlarged on the end thereof, and the enlargement provided with a plane cylindrical surface, and other changes may be made without departing from my invention as defined 70 in the appended claims.

I claim:

1. A golf club comprising a tubular metal shaft and a non-metallic head, the contacting surfaces of the head and shaft being fluted to prevent relative turning movement of the head and shaft. 75

2. A golf club comprising a tubular metal shaft and a non-metallic head, the end of 80 the shaft having an enlargement to which the head of the golf club is attached and the contacting surfaces of the head and shaft being fluted to prevent relative axial movement of the head and shaft. 85

3. A golf club comprising a tubular metal shaft and a non-metallic head, the contacting surfaces of the head and shaft being fluted, the metal shaft having an integral enlargement on its end to which the head 90 of the golf club is attached.

4. A golf club comprising a tubular metal shaft and a non-metallic head, the tubular metal shaft having an integral enlargement on its end to which the head of the golf club 95 is attached, and the surface of said enlargement having a series of parallel flutes in the outer surface thereof to engage the neck of the head and prevent turning of the head on the shaft. 100

In testimony whereof, I have hereunto set my hand.

JOHN W. OFFUTT.
